UNITED STATES PATENT OFFICE

WILLIAM CUNNINGHAM, OF MOUNT KISCO, NEW YORK

CLOSURE FOR OPENINGS IN BUILDINGS

Application filed March 26, 1930. Serial No. 439,182.

My said invention relates to closure for openings in buildings and is suitable for embodiment in an outer door or window, a screen door, a storm door or window, a louvre, a cellar sash, etc. It is an object of my invention to provide improved means whereby such closures are readily convertible. For example, a storm window or door may be quickly changed into a screen door or a window screen without any tools or need for skilled labor.

Another object of my invention is to provide means whereby panes of glass or the like can readily be washed by a person inside a house, without going outside the building, as one may take the glass out and wash it at leisure.

Another object is to provide improved means to hold a removable window pane or the like securely in place without possibility of rattling.

Another object is to provide drainage means for the closure.

Referring to the drawings, which are made a part of this application and in which similar reference characters indicate similar parts:

Fig. 1 is an elevation of one form of my device,

Fig. 2, a section on line 2—2 of Fig. 1.

Fig. 3, a section on line 3—3 of Fig. 1,

Figs. 4, 5 and 6, elevations similar to Fig. 1 but showing devices other than panes of glass positioned to close the apertures,

Fig. 7, an end elevation of a part shown in Fig. 5, and,

Fig. 8, an end elevation of a part shown in Fig. 6.

In the drawings reference character 10 indicates a part of a building or the like in which a window frame is mounted by means of hinges 11 secured to a stile 12. For purpose of illustration the invention has been illustrated as embodied in a window having a frame comprising stiles 12 and 13, a top rail 14, a center rail 15 and a bottom rail 16. The window also includes upper and lower sashes 17 and 18 forming no part of my invention and therefore not more specifically described. The frame members 13, 14, 15 and

16 are provided with rabbets as clearly shown at 19 in Fig. 3 for guiding and holding in place a window pane or the like and the stile 12 is provided with upper and lower slots 20, the upper and lower limits of which are indicated by dash lines in Fig. 1, for receiving a window pane or the like and guiding it into place, these slots being in line with the rabbets 19. For clamping the panes in place to prevent rattling and to exclude wind and rain I have shown in Fig. 2 eccentrics 21 which are rotatably mounted so as to bear against the window panes or the like and force them against the opposed walls of the rabbets 19. Drainage passages 22 (Fig. 2) lead from suitable parts of lowermost rabbets 19 to carry off water.

In Figs. 4, 5 and 6 I have illustrated some of the possibilities of my invention, Fig. 4 showing screens 23 as having been substituted for the panes of the glass illustrated in Fig. 1. The screens have frames 24 as usual and may be made up in any suitable manner. For example they may have central vertical stiles to strengthen them and improve their appearance or they may be made up after the manner of a casement or a pair whereby each of them would be pivoted at the side remote from the center of the window so as to be swingable to open position.

Fig. 5 shows ventilators 25 as having been substituted for the window panes. These also may be made up in any suitable manner and preferably have side flanges 26 and 27 (Fig. 7) fitting fairly closely in the rabbets 19 to prevent excessive rattling or they may be provided with such anti-rattling means as shown in Fig. 2. It will be understood that other suitable means may be employed for this purpose.

Fig. 6 illustrates a window having sheet metal members 28 substituted for the window panes, as may be done when a house is closed for the season or when for other reasons it becomes desirable to guard against intrusion. Preferably such sheet metal members have lateral flanges 29 fitting with reasonable closeness in the rabbets 19 to limit rattling. As will be understood the metal members may be varied in form and contour in many ways.

without departing from the spirit of the invention. In some instances, as in the case of cellar sashes it may be desirable to provide means for retaining the window panes or other sheet-like members in place and for this purpose I have indicated set screws 30 in Fig. 6 which may be set up against the sheet-like members, it being understood that in a cellar sash the longer dimension of the opening is horizontal.

10 A similar result may be had by providing adjustable moldings on the frame in such manner that they may be forced up against the sheet-like members by means of screws 15 having eccentric heads, as is well understood by those skilled in the art, such moldings taking the place of the set screws 30 or the eccentrics 21 and both, and other means for this purpose will suggest themselves to those 20 skilled in the art.

It will be obvious that my improvements can be applied to screen doors or storm doors as well as to window screens and storm windows or to ordinary exterior doors or windows as desired as well as to cellar sash, louvres or to any other closure for openings in buildings, boats and the like. Clearly also such device may be made of metal instead of wood and may be adapted in other ways. In 25 the example shown in the drawings hinges are provided such as will throw the window sash or door away from the wall of the building when fully opened thereby permitting better access to the sheet-like member to be 30 withdrawn or positioned. Beads or bead felt may be applied in well known manner and in general it will be obvious that many changes may be made in the device shown and described without departing from the 35 spirit of my invention and therefore I do not limit myself except as indicated in the appended claim.

Having thus fully described my said invention, what I claim as new and desire to 40 secure by Letters Patent, is:

A convertible storm window or door for wall opening reveals comprising top, bottom and intermediate rails connected by stiles, rabbets about the window openings formed 45 by said rails, and spaced slots at intervals in the length of the rear stile corresponding in length and position to the window openings whereby a sheet-like closure element may be readily placed in each of said openings, removed therefrom or interchanged with another, and means on the rear stile adjacent each slot and cooperating with the side of the wall opening reveal to draw the slotted length of the stile into contact therewith to close 50 said slots and prevent unauthorized removal of said removable closure elements.

In testimony whereof I affix my signature.

WILLIAM CUNNINGHAM.
